(57) **CLAIM**

The ornamental design for a ceiling fan blades unit, as shown and described.

DESCRIPTION

FIG. 1 is a front elevation view of the ceiling fan blades unit showing my new design;

FIG. 2 is a side elevation view thereof, the opposite side plan view being identical;

FIG. 3 is a bottom plan view thereof;

FIG. 4 is a top plan view thereof viewed; and,

FIG. 5 is a perspective view thereof.

The support rod has been shown broken away in FIGS. 1-5 to indicate indeterminate length.
